INVENTOR.

Wm. Johnson

United States Patent Office.

WILLIAM JOHNSON, OF MILWAUKEE, WISCONSIN.

Letters Patent No. 106,169, dated August 9, 1870.

IMPROVEMENT IN HINGES.

The Schedule referred to in these Letters Patent and making part of the same.

To all whom it may concern:

Be it known that I, WILLIAM JOHNSON, of the city and county of Milwaukee, and State of Wisconsin, have invented a new and useful Improvement in Blind-fastening Hinges; and I do hereby declare that the following is a full, clear, and exact description thereof, which will enable those skilled in the art to make and use the same, reference being had to the accompanying drawing forming part of this specification, in which—

Figure 1 is a perspective view of my invention;

Figure 2, a sectional view; and

Figure 3 is a view of the bottom of the pintle, with the stop on it.

Similar letters of reference in each of the figures indicate corresponding parts.

My invention consists in providing a button or cam at the lower end of a feathered pintle, whereby the same is prevented from being accidentally lifted out of the socket.

A is the lower leaf of the hinge.

B is the upper leaf.

C, the pintle, made hollow.

D, the fastening-bolt, with a feather on its side, fitting in slots in the leaves.

E, slots in the leaves for the feather on the fastening-bolt to fit in.

F, a piece fastened on the lower end of the fastening-bolt D, which, when turned on the pin G, which holds it on, will prevent the bolt from being withdrawn and the blind coming off the hinge.

H, a piece screwed onto the top of the lower leaf, with a point projecting out over the cap of fastening-bolt D, which also prevents the bolt from rising out of place, and thus the blind is held in position.

I, feather on bolt D.

Operation.

When the blind is hung and closed, as shown, fig. 1, the feather falls into the slot, and the fastener D is down to its place, and the blind is held to. To open the blind, just raise bolt D till the upper part of the feather comes out of the slot in the upper leaf, and the blind can be swung back, and when back far enough for the feather to come over the other slot, bolt D falls down in place, and the hinge is held open. And to close it again, raise bolt D, and the work is done. The piece F, on the lower end of bolt D, when turned round, prevents bolt D from being raised out of place, the end of it projecting out, as shown, fig. 3, and the piece H will also prevent the blind from being raised off the hinge, or the wind from blowing it off.

Claim.

I claim as my invention—

Button or cam F, at the lower end of pintle D, to prevent said pintle from being accidentally lifted out of its socket.

WM. JOHNSON.
